C. P. Goepel

UNITED STATES PATENT OFFICE.

HARRY LEBERMAN, OF NEW YORK, N. Y., ASSIGNOR TO GROOVE LOCK CO. INC., OF NEW YORK, N. Y., A CORPORATION OF NEW YORK.

VANITY CASE.

Application filed November 17, 1927. Serial No. 233,777.

This invention relates to improvements in containers, such as vanity cases and the like, and has particular reference to a novel hinge connection and holding means for cases with 5 circular outlines.

There is considerable demand for circular containers with hinged covers, but prior to this invention, it has been difficult to provide such a container with a hinge of suitable 10 mechanical strength. It has been customary to form the hinges of straight wire or the like and arrange the same substantially tangent to the edge of the container. In order to do this, it has been necessary to provide a hinge 15 lug which extends a substantial distance from the edge wall of the container, or to provide the hinge pin of such a short length as to have an inadequate bearing. Naturally, hinge lugs which project too far from the edge 20 of the container detract from the appearance of the device, and particularly with respect to vanity cases, the question of appearance is of vital importance in its desirability.

It is therefore an object of the present invention to provide a hinge connection with circular cases, wherein the hinge pin has a relatively long bearing, yet, the connection will extend only a minimum distance from the edge of the case.

Another object is to provide a novel and simplified means for maintaining the case sections in closed relation.

Another object is to provide a vanity case of extremely simple construction, of neat appearance, strong and durable in service and constituting a substantial advance in the art.

With these and other objects in view, the invention resides in the novel features of construction, combination and arrangement of parts hereinafter set forth, shown by way of illustration in the accompanying drawings and specifically pointed out in the appended claims.

In the drawings forming a part of this application,

Figure 1 is a top plan view of the improved vanity case with the parts in closed and locked position.

Fig. 2 is a front edge view of the same 50 partly broken away and partly in section.

Fig. 3 is a view similar to Fig. 1, but showing one of the case sections as having been rotated with reference to the other.

Fig. 4 is a transverse sectional view on line

4—4 of Fig. 3, showing more clearly the novel 55 bayonet slot connection, and

Fig. 5 is a side elevation of the case with the parts in open relation.

Referring now particularly to the drawings, the novel vanity case has been shown as 60 comprising a pair of case sections 10 and 11, having opposed open sides and being hingedly connected together as at 12. Sections 10 and 11 may be conveniently formed of sheet metal 65 or the like, and respectively include a bottom wall 13 surrounded by a circumferential edge wall or rim 14 and a top wall 15 having an integral edge wall or flange 16. Said case sections are circular in outline, as best shown in Figures 1 and 3 and the edge wall 13 of 70 the section 11 is preferably spun or otherwise offset to provide a peripheral flange 17 which is adapted to fit within the edge wall 14 of the section 10.

Secured to or integral with the edge wall 75 14 of the casing section 10 is a hinge member 18 having an aperture 19 which is curved concentrically with respect to the periphery of the wall 14, and the casing section 11 is similarly provided with a hinge member 20 having 80 an aperture 21 of the same radius of curvature as the aperture 19 and adapted to be aligned therewith. A hinge pintle 22 extends through the apertures 19 and 21 of said hinge members and is preferably of a length 85 greater than the combined length of said hinge members. By virtue of this arrangement, one extremity of the hinge pintle extends beyond the end of the hinge member 20 when the case is closed and locked, as shown 90 in Figure 1, and furthermore, the casing section 11 is adapted to be rotated with reference to the section 10 about their common axes. In said rotation, the hinge member 20 moves longitudinally upon the pintle 22.

At a suitable point, preferably diametrically opposed to the hinge connection, the flange 17 is provided with a bayonet slot 23 which is adapted to receive a locking pin 24 carried by the edge wall 14 of the other case 100 section. The arrangement is such that when the parts are related, as illustrated in Figures 3 and 4, the case section 11, which is in effect a hinged cover, may be moved toward and away from the case section 10. In order 105 to close the case and lock it, said section 11 need only be swung down against the section 10 and partially rotated to bring the pin 24

into locking engagement with the bayonet slot 23, as best shown in Figure 2. In order to permit the relative swinging movement, it will be evident that the pindle 22 must necessarily be slightly yieldable, whereby to compensate for the difference in curvature in its different planes.

From the foregoing, it will be evident that an improved vanity case or similar container has been provided, wherein the parts are of extremely simple construction and capable of being produced at relatively low cost. The invention is, of course, susceptible of numerous modifications in the details of construction and arrangement of parts, and the right is herein reserved to make such changes as fall within the scope of the appended claims without departing from the spirit of the invention.

Having thus described my invention, what I claim is:—

1. A container of the class described, comprising a pair of casing sections having rims hingedly connected together, the hinge connection being so formed as to permit rotation of one of the casing sections with reference to the other, said sections having interengaging parts to secure the sections together or release same upon such rotation.

2. A container of the class described, comprising a pair of casing sections having rims hingedly connected together, the hinge connection being so formed as to permit rotation of one of the casing sections with reference to the other, and mutually engaging pin and bayonet slot for holding the casing sections in closed relation, or for releasing said sections with such rotation.

3. In a vanity case or the like, a pair of substantially circular case sections having opposed open sides, one of said case sections having a circumferential flange adapted to fit within the other section, said flange being provided with a bayonet slot, and the other case section being provided with an inwardly extending pin to engage in said slot, hinge lugs carried by the case sections in diametrically opposed relation to said slot and pin, and a curved hinge pindle connecting said case sections through the hinge lugs, said hinge pindle permitting relative rotation of the case sections about their common axes and being yieldable to permit opening and closing of the case.

In testimony that I claim the foregoing as my invention, I have signed my name hereto.

HARRY LEBERMAN.
